(57) **CLAIM**

The ornamental design for a display screen with icon, as shown and described.

DESCRIPTION

FIG. 1 is a front view of a display screen with icon showing the new design; and,

FIG. 2 is a front view of a display screen icon showing an alternative embodiment of the new design.

The broken line showing of the remainder of the display screen is for environmental purposes only and forms no part of the claimed design. Applicants reserve the right to disclaim, by amendment or in a continuation application, the square frame surrounding the icon.

FIG. 2

UNITED STATES PATENT AND TRADEMARK OFFICE
CERTIFICATE OF CORRECTION

PATENT NO. : D669,498 S
APPLICATION NO. : 29/401405
DATED : October 23, 2012
INVENTOR(S) : Phelan

Page 1 of 4

It is certified that error appears in the above-identified patent and that said Letters Patent is hereby corrected as shown below:

Delete title page and substitute therefore with the attached title page consisting of corrected illustrative figures.

In the Drawings

Figs. 1-2 should be replaced with the corrected Figs. 1-2 as shown on the attached pages.

Signed and Sealed this
Eleventh Day of February, 2014

Michelle K. Lee
Deputy Director of the United States Patent and Trademark Office
